UNITED STATES PATENT OFFICE.

GOTTLIEB F. ZUCKER, OF BERWYN, ILLINOIS.

AUXILIARY PRIMING AND AIR-CONTROLLING DEVICE FOR INTERNAL-COMBUSTION ENGINES.

1,306,210.

Specification of Letters Patent. Patented June 10, 1919.

Application filed April 3, 1918. Serial No. 226,427.

To all whom it may concern:

Be it known that I, GOTTLIEB F. ZUCKER, a citizen of the United States, and a resident of the city of Berwyn, county of Cook, and 5 State of Illinois, have invented certain new and useful Improvements in Auxiliary Priming and Air-Controlling Devices for Internal-Combustion Engines, of which the following is a specification.

10 My invention relates to improvements in auxiliary priming and air controlling devices for internal combustion engines, and has for its object the production of a device of this character through the medium of 15 which an engine may be readily and easily primed to facilitate starting of the same and whereby the air supplied to the engine after the latter has started may be controlled in order to obtain the best possible mixture and 20 still conserve fuel.

With these objects in view, the invention consists in the combinations and arrangements of parts hereinafter described and claimed.

25 The invention will be best understood by reference to the accompanying drawings forming a part of this specification, and in which,

Figure 1 is a side elevation of a device embodying the invention,

Fig. 2 a top plan view of the device,

Fig. 3 a central vertical section of the device, and

Figs. 4, 5 and 6 are horizontal sections 35 through the device showing the various positions assumed by the movable element thereof in the control of the passage of gas and air therethrough.

The preferred form of construction as 40 illustrated in the drawings comprises a plate 7 which is provided with a bracket 8 whereby the same may be rigidly mounted upon the dash board or other suitable support on the automobile in connection with which the device is used. The plate 7 is provided with a circular recess 9 at its upper side which is adapted to snugly receive the lower end of the body part 10 of the device which is rotatably mounted upon said plate 7.

50 The member 10 is hollow and preferably of conical form, the same being connected with the plate 7 by means of a bolt 11 which passes loosely through the member 10, the lower end of said bolt being threaded into the plate 7. A helical compression spring 12

is interposed between the head of bolt 11 and the upper side of member 10, said spring serving to hold the parts 7 and 10 in close engagement with each other. A suitable packing 13 arranged at the upper side of member 10 embraces the bolt 11 to prevent leakage.

Connected with the under side of plate 7 is a fuel supply pipe 14 which, in practice, connects with the source of gasoline or any other hydrocarbon used in connection with the vehicle. Formed in the lower end of bolt 11 is a passage 15, the lower end of which communicates with the supply pipe 14, the upper end of said passage being in open communication with the interior of member 10.

Formed in the plate 7 is an elongated air opening 16 and an outlet opening 17, and a pipe 18 leading from the opening 17 for communication, in the installation of the device, with the intake manifold of the engine in connection with which the device is used. Formed in the under side of member 10 for registration with the opening 16 is an 80 opening 19 of corresponding form, and also formed in the under side of member 10 are two spaced openings 20 and 20' adapted for individual registration with the opening 17. The openings 20 and 20' are so arranged 85 that, when the opening 20 is in full registration with the opening 17, opening 19 will be in full registration with the opening 16 as clearly as seen in Fig. 4, and, when the opening 20' is in full registration with the 90 opening 17, the opening 19 will be out of registration with opening 16. Moreover openings 20 and 20' are spaced apart at such a distance that, when the member 10 is in intermediate position, that is a position mid- 95 way between the two positions above mentioned, the openings 17 will be registering with neither 20 or 20'. This rotary adjustment of the member 10 is effected through the medium of a suitable handle or lever 21 100 and a finger 22 on the member 10 co-operating with the graduations 23 on the plate 7 serves to indicate the positions of said member 10.

With the construction set forth, it will be 105 seen that when it is desired to prime the engine as in the starting of the latter, it is only necessary to rotate the member 10 to the position seen in Fig. 6, or to a position in which opening 20' will be in registration 110

with opening 17 and opening 19 will be out of registration with opening 16. When the member 10 is in this position, upon turning over of the engine, the suction of the cylinders will cause a partial vacuum to be created in member 10 which will have the effect of drawing fuel thereinto through the pipe 14 and passage 15; the fuel thus drawn into member 10 passing through pipe 18 into the intake manifold of the engine, thus serving to prime the same and facilitate starting.

When it is desired to adjust the supply of air, it is only necessary to shift the member 10 to the position seen in Fig. 4. In this position, upon suction being created by the engine pistons, air will be drawn through openings 16 and 19 into the member 10 and thence to the intake manifold of the engine. The openings 16 and 19, being relatively much larger in size or cross section than the passage 15 and opening into free outer air, the suction of the engine cylinders will have practically no effect on the longer and deeper passage 15, or the effect will be so slight that no gas or fuel will be drawn through said passage. Thus when the opening 19 is in full registration with the opening 16 nothing but air will be fed to the engine. Through adjustment of the member 10 it will be seen that the supply of air to the engine cylinders may be readily and easily controlled. Where it is desired to supply neither fuel nor air to the engine, the member 10 is adjusted to the position seen in Fig. 5, when communication with the opening 17 is closed.

While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

Having described my invention, what I claim as new and desire to secure by Letters Patent is:

1. In a device of the class described, a fuel supply nozzle, a mixture conducting pipe having an entrance in proximity to the supply nozzle, a casing forming a hollow chamber entered by the fuel supply nozzle and the entrance of said mixture conducting pipe, there being an air intake port in said chamber of greater size than the opening in the conducting pipe, and a valve plate carried by the hollow chamber movable to control the air intake opening and the entrance to the mixture conducting pipe, provided with an opening approximately the size of the air intake opening, adapted to in one position, register therewith to admit air into said chamber, and provided with a plurality of spaced openings adapted to independently

register with the intake opening of the mixture conducting pipe to allow the contents of the chamber to pass from said chamber to the mixture conducting pipe, the whole so arranged that the mixture conducting outlet opening may, by properly positioning the valve member, at the will of the operator, be wholly closed or wholly opened, and that when it is opened, the air intake opening will be selectively wholly closed or open, depending on which valve opening for said mixture conducting pipe opening is in register therewith, for the purposes set forth.

2. A device of the class described comprising a stationary plate having an air inlet opening and an outlet opening; a body part having a chamber therein; and a fuel supply in open communication with said chamber, said body part being rotatably mounted on said plate and having an air inlet opening adapted for registration with said air inlet opening of said plate; and having a plurality of spaced outlet openings adapted for individual registration with said outlet opening of said plate, said openings being of such relative proportions and relatively so arranged that outlet from said chamber can be effected with the air inlet to said chamber either closed or wholly or partly open, substantially as described.

3. A device of the class described comprising a stationary plate having an air inlet opening and an outlet opening; a body part having a chamber therein; and a fuel supply in open communication with said chamber, said body part being rotatably mounted on said plate and having an air inlet opening adapted for registration with said air inlet opening of said plate, and having a plurality of spaced outlet openings adapted for individual registration with said outlet opening of said plate, said openings being of such relative proportions and relatively so arranged that outlet from said chamber can be effected with the air inlet to said chamber either closed or wholly or partly open, and means for yieldingly holding said body part and plate in close engagement with each other, substantially as described.

4. A device of the class described comprising a stationary plate having an air inlet opening and an outlet opening; a body part having a chamber therein; a fuel supply in open communication with said chamber, said body part being rotatably mounted on said plate and having an air inlet opening adapted for registration with said air inlet opening of said plate, and having a plurality of spaced outlet openings adapted for individual registration with said outlet opening of said plate, said openings being of such relative proportions and relatively so arranged that outlet from said chamber can be effected with the air inlet to said chamber

- either closed or wholly or partly open, and means for holding said body part and plate in close engagement with each other, said means comprises a bolt connecting said parts, there being a passage formed in said bolt for the fuel supply, substantially as described.
5. A device of the class described comprising a stationary plate having an air inlet opening and an outlet opening; a body part having a chamber therein; a fuel supply in open communication with said chamber, said body part being rotatably mounted on said plate and having an air inlet opening adapted for registration with said air inlet opening of said plate, and having a plurality of spaced outlet openings adapted for individual registration with said outlet opening

of said plate, said openings being of such relative proportions and relatively so arranged that outlet from said chamber can be effected with the air inlet to said chamber either closed or wholly or partly open; a bolt connecting said body part and plate; and a helical compression spring co-operating with said bolt for yieldingly holding said parts in close engagement with each other, substantially as described.

In testimony whereof I have signed my name to this specification in the presence of two subscribing witnesses.

GOTTLIEB F. ZUCKER.
